UNITED STATES PATENT OFFICE.

EDWARD JONES, OF LEEDS, COUNTY OF YORK, ENGLAND.

DYNAMO-ELECTRIC MACHINE.

SPECIFICATION forming part of Letters Patent No. 321,609, dated July 7, 1885.

Application filed September 8, 1884. (No model.)

To all whom it may concern:

Be it known that I, EDWARD JONES, of Westhill Terrace, Chapel Allerton, Leeds, in the county of York, England, have invented 5 certain new and useful Improvements in Dynamo-Electric Machines, of which the following is a specification.

This invention relates to an improved electric generator, the objects in view being to 10 reduce the cost of construction and increase the efficiency of the machine. This improved electric machine has only a single shaft-bearing, the driving-pulley being keyed to one end of the shaft, and the armature and commutator being mounted closely together on 15 the other end thereof. The field-magnets are formed with deeply-channeled pole-pieces, between or in front of which the armature rotates, and the shanks or cores of the said 20 field-magnets are arranged parallel to the armature-shaft, and are separately wound.

The invention also relates to various improvements in the details of construction and combination of parts, which are hereinafter 25 fully described and claimed.

The details of construction and general arrangement of this improved electric generator will be understood on reference to the accompanying drawings, in which—

30 Figure 1 is an elevation of the machine as seen from the end at which the commutator and armature are situate. Fig. 2 is a central longitudinal section of the machine. Fig. 3 is a front view of the armature with only one 35 coil in place, the better to illustrate the manner in which the armature is constructed and mounted on its spindle; and Figs. 4, 5, and 6 are detail views of about one-half the actual size of the brush-rocker and brushes.

40 In these figures the same letters of reference indicate like or corresponding parts.

The main frame of the machine consists of a single end plate or standard, A, which carries the single long bearing B for the spindle 45 C of the armature D, and also the cores or shanks e e of the field-magnets E E. For convenience in fitting, these cores or shanks e e are attached to the frame or standard A by screw-bolts, and the segmental pole-pieces e' e' 50 of the field-magnets are rigidly connected by a ring or light frame, F, of diamagnetic material or metal—such as brass—to prevent any

vibration at that end of the machine. A block, G, of wood or other diamagnetic material, is bolted to the pole-piece e' of the 55 lower magnet or magnets, and serves as a foot or support for the said magnet or magnets, and (in case the machine is fixed on an iron bed-plate) this block G insulates the pole piece or pieces or holds them at a distance 60 from the said bed-plate. The ring or frame F, besides preventing the vibration of the field-magnets E E, serves also as a guide or race for the brush-rocker H, the construction of which and the mode of mounting the 65 brushes with respect to the commutator will be fully explained hereinafter.

I is the commutator, fast on the shaft C, and arranged in close proximity to the armature D; and J is the driving-pulley, fast on the 70 other end of the shaft C. The single long bearing B for the armature-spindle is preferably cast in one with the end plate or standard of the machine, to which the field-magnets are bolted, and is made hollow and slightly 75 taper for strength and lightness. As the bearing B is hollow or chambered to within a short distance from each end, it is only necessary to accurately bore it for a small portion at its inner and outer ends to receive the bush b for 80 the spindle, and this bush, which may be of any usual and suitable material, and may be cast, only requires turning at its extremities or parts where it is fitted closely into or against the cast-metal bearing or support B. 85 The bush b is preferably channeled or cast with a reduced diameter between its turned extremities, and is of course accurately bored to receive the spindle C.

This construction is very simple and facilitates the accurate fitting together of the machine.

Such being the general construction and arrangement of the frame-work and field-magnets, I will now proceed to describe the way 95 in which the armature of my improved machine is constructed and mounted.

The pole-pieces d d of the armature D, I arrange or group in pairs around the hub D', separating the inner and outer ends of each 100 pair of pole-pieces by spacing-blocks d' d', of wood or equivalent non-conducting material, and securing them together in that position by bolts or clips, (seen in Fig. 2,) also of non-

conducting material, by which construction and arrangement I prevent the creation of induced currents in and around the pole-pieces of the armature, and facilitate the circulation 5 of air. The pole-pieces d are of **U** shape, having their outer ends left open instead of being closed by filling-pieces, and may be conveniently formed by stamping out of soft-iron plate.

10 The core D^2 is composed of a thick coil of soft-iron wire wound on a former, or of iron in any other well-divided form wound with cotton or other fibrous material, and varnished, or varnished only without being wound with 15 cotton. The hub D' of the armature is of slightly taper form, and made of a non conducting material. It is preferably built up of segmental blocks of wood having the end of the grain facing outward or radiating from 20 the center, to prevent alteration in diameter due to expansion or contraction, and these blocks of wood, when such are used, are bound together by brass side plates and screws.

The hub thus constructed of insulating material is keyed fast on the spindle C . The pole-plates d , connected in pairs, as above described, are disposed radially around the hub, and serve to force outward the iron core D^2 and hold it concentric with the spindle. The 30 inner ends of the pole-pieces are cut rather obliquely, so as to fit onto the slightly taper hub D' , and are held thereon by washers or collars D^3 , which are forced against them by nuts threaded on the spindle C , as will be well 35 understood, the said washers or collars D^3 being insulated from the metal of the armature by collars or rings of insulating material d^2 , as shown in Fig. 2.

The fan-shaped sections, into which the core 40 D^2 is divided by the pairs of pole-pieces d , are wound with the required number of coils or bobbins of insulated copper wire or tape in such a manner as to fill each of the said sections or spaces. I preferably divide the 45 armature into twelve sections, each having six bobbins of wire wound thereon.

By means of suitable adjusting screws and nuts, the bush b , and with it the spindle C , can be shifted endwise, and the armature be 50 thereby adjusted to its field. Any liability to endwise movement of the shaft C may be prevented by means of nuts C' on the pulley end of the shaft, which nuts serve also to take up any wear on the collars of the shaft. These 55 adjusting-nuts could also be arranged in immediate proximity to the flange b' of the bush b , if desired.

The commutator I , of any convenient construction, is keyed on the spindle C , close 60 against the armature D , and as there is no bearing at all needed for the spindle on the commutator side of the armature, and no field-magnet shanks or cores are present at that part to interfere with the connections, 65 the said connections may be made direct and short, and are always easily accessible. No necessity, moreover, exists for drilling the

spindle for the passage of the conducting-wires from the armature to the commutator, and the spindle therefore remains unweakened at this 70 part.

I would here remark that I make no claim to any improvement in the construction of the commutator itself.

The brushes H' , I make of a number of 75 straight copper wires bound together to form a broad flat surface, (see Fig. 5,) or of flat strips of copper set edgewise side by side, (see Fig. 6.) and arranged to present their ends or end edges to the commutator-plates, and I cause these brushes H' to be fed forward by a light spring or springs, h , or their equivalent, which tends to push the brushes lengthwise through a suitably-formed guide case or sheath, h' , against the periphery of the 85 commutator I .

The angle at which the brushes H' meet the commutator may vary within considerable limits; or the brushes may even be set truly radial to the commutator, as shown in full 90 lines in Figs. 1 and 4, the object in view being to maintain the rubbing area constant, whereas in tangentially - arranged brushes, such as are commonly used, the area of contact tends to rapidly increase and to impair 95 the efficiency of the machine. I preferably adjust the brushes to the position shown in dotted lines in Fig. 4.

The guides or cases h' , through or against which the brushes of wire or copper strips 100 pass or are fed forward, and which also carry the spring or equivalent devices h , for feeding them toward or against the commutator, are mounted on a ring of metal, H , provided with a handle, X , (see Figs. 1 and 2,) for rotating 105 or rocking it, and thereby varying the lead of the brushes. This handle X also serves as a clamping-screw for securing the brush-rocker in position. This brush-rocker H is mounted to slide, as in a bearing, against a stiffening 110 plate or frame, F , which rigidly unites the pole-pieces of the field-magnets E E ; and the ring H is retained in place by a covering-plate, K , of card or leather board, vulcanite, or other suitable material secured to the stiffening plate or frame by screws. This annular covering-plate K conceals the connections 115 between the armature and commutator, and protects them from injury.

This improved machine is compact and 120 light, and, owing to the simplicity of the construction and arrangement of the several parts, can be readily fitted together or dismantled. The commutator and armature connections are greatly simplified, and so situate as to be 125 easy of access, while the armature is light, rigid, easily adjustable, free from disturbing currents, and not liable to heat.

I may use field-magnets having two, four, six, or more poles; but I have obtained excellent results from a magnet having two shanks, e e , secured at their one ends to the endstandard, A , and having at their other ends deeply-channeled pole-pieces, the shanks or cores of the 130

magnet being parallel with the shaft of the armature.

This machine may be used with but slight alteration as an electric motor.

5 Having now described the nature of my several improvements in dynamo-electric machines, I wish it to be understood that I claim—

1. In a dynamo electric machine, the combination, with a single standard or end plate carrying a single long bearing and an armature mounted upon a spindle adapted to rotate within the said single bearing, of two or more channelled pole-pieces, each having a separately-wound core or shank secured to the said single end plate and arranged parallel to the armature-spindle, and a commutator mounted on the said spindle in close proximity to the armature and at that side thereof which is remote from the single end plate or standard of the machine, substantially as and for the purpose set forth.

2. In a dynamo electric machine, the combination, with a standard or end plate carrying a single long central bearing and an armature and commutator mounted close together on one end of a spindle, of one or more pairs of separately-wound electro-magnets bolted to the said standard, with their pole-pieces supported at a distance from the bed-plate, and a frame or ring of brass or its equivalent connecting the said pole-pieces, and serving as a bearing or guide for the brush-rocker, substantially as set forth.

3. In a dynamo-electric machine, the combination, with the standard or end plate, A, a single long central bearing, B, separately-wound electro-magnets E E, spindle C, armature D, and commutator I, of a bush, b, fitted 40 within the bearing, means, substantially as described, for adjusting the said spindle lengthwise within the said bush, and a brush rocker, H, mounted upon a frame or ring, F, connecting the pole-pieces of the electro-magnets, and 45 serving to prevent their vibration, all substantially as set forth.

4. An armature for dynamo-electric machines, consisting of a soft-iron core supported on U-shaped iron pole-pieces arranged radially 50 in pairs around a hub of non conducting ma-

terial, the pole-pieces in each pair being separated the one from the other by spacing-blocks of insulating material, and the several pairs of pole-pieces being secured on the hub and dividing the core into fan-shaped sections 55 for the reception of the coils of conducting-wire, substantially as described, and for the purpose set forth.

5. In a single-bearing dynamo-machine, the combination, with the armature D, field-magnets E E, commutator I, and brush holder and rocker H, of the diamagnetic ring or frame F, forming a rigid connection between the pole-pieces of the said field-magnets, and also a bearing or guide for the brush-rocker, and the 60 covering plate or ring K, for retaining the said brush-rocker in place, and serving to conceal and protect the connections between the armature and commutator, substantially as described with reference to the drawings. 70

6. In a dynamo-electric machine, the combination, with a commutator, of a brush or collector consisting of a number of wires or strips of metal packed closely together, so as to present their ends in a line or lines parallel to the commutator-bars, a guide or sheath for the brush, and a spring, whereby the brush is automatically and constantly pressed or fed forward through the guide or sheath in a radial or nearly radial direction against the 75 periphery of the commutator, for the purpose of maintaining constant the rubbing area of the brush and holding it steadily to its work, substantially as herein set forth.

7. In a dynamo-electric machine, the combination, with the commutator I, of the brush-rocker H, brushes H', guide cases or sheaths h', and springs h, or their equivalent, substantially as described, for the purpose of automatically imparting a forward feed to the 80 brushes in a radial or nearly radial direction with respect to the commutator, and thereby maintaining constant their rubbing area, as set forth.
